UNITED STATES PATENT OFFICE.

JAMES C. KOCONTES, OF CUPERTINO, CALIFORNIA.

HORSESHOE.

1,145,247.

Specification of Letters Patent.

Patented July 6, 1915.

Application filed February 15, 1915. Serial No. 8,128.

To all whom it may concern:

Be it known that I, JAMES C. KOCONTES, a subject of Greece, and a resident of Cupertino, Santa Clara county, and State of California, have invented a certain new and useful Horseshoe, of which the following is a specification.

The invention relates to horseshoes and particularly to the means of attaching the shoe to the hoof of the horse.

10 An object of the invention is to provide an improved means for attaching the shoe to the hoof.

Another object of the invention is to provide a horseshoe which produces a tractive grip on the roadway or pavement, thereby preventing slipping.

15 The invention possesses other advantageous features, which, with the foregoing, will be set forth at length in the following description, where I shall outline in full that form of the invention which I have selected for illustration in the drawings accompanying and forming part of the present specification. The novelty of the invention will be included in the claims succeeding said description. From this it will be apparent that I do not limit myself to the embodiment of the invention illustrated 20 in the drawings, as I may adopt many variations within the scope of my invention as set forth in said claims.

25 Referring to said drawings: Figure 1 is a vertical section of the horseshoe of my invention. Fig. 2 is a vertical section taken on the line A—A Fig. 1. Fig. 3 is an underneath view of one-half of the shoe of my invention. Fig. 4 is a vertical section of a shoe of slightly different form with the attaching means of my invention arranged thereon. Fig. 5 is a section taken on the line B—B Fig. 4. Fig. 6 is a front view of a hoof showing the shoe attached thereto.

30 The body 2 of the horseshoe of my invention is of the same shape as the ordinary horseshoe. Along its outer edge at opposite sides of the shoe the body is provided with a plurality of substantially vertical slots 3 and adjacent each slot there is provided an aperture 4 extending through the body. Secured in each aperture 4 is a nail 5, the body portion 6 of which is bent upward, so that it extends upwardly at an angle to the shoe. The sharpened end 7 of the nail is bent in-

ward, so that when the shoe is placed against the hoof the ends 7 point toward the hoof. In this condition the body of the nail is partially disposed in the slot 3, so that the nail cannot rock sidewise. When the shoe is attached, the end 7 is driven into the hoof and the body portion of the nail is bent so that it is fully disposed in the slot, the sides of which brace the nail and insure a rigid connection between the nail and the shoe. By being disposed in the groove the body of the nail is not subjected to the wear that it would receive if it projected laterally from the shoe.

35 At the toe of the shoe is arranged a broad fastening member 8, which projects upward and which is pointed and turned inward at its upper end. The base of the member 8 seats in a depression 9 formed in the upper surface of the shoe and the member is held in place by projections 12 which engage the apertures 13 in the shoe. When the shoe is applied the pointed end of the member 8 is also driven into the hoof.

40 The shoe is preferably provided on its under side with a plurality of triangular projections or plinths 14, which are so disposed that an apex of at least one triangle points in the direction in which the shoe is liable to slip as the horse travels over smooth or slippery surfaces. These projections produce a substantially positive grip on the road surface and prevent slipping. These projections also prevent the excessive wearing of the nails 5 at that portion where they pass over the under surface of the body, between the slots 3 and the apertures 4.

45 When it is desired to apply the fastening means of my invention to a shoe having a smooth under surface or one having calks only at the heel and toe as shown in Figs. 4 and 5, the body of the shoe is provided on its under surface with slots 16 extending from the apertures 4 to the slots 3, in which the portion of the nail lying between the slot and the aperture is disposed. The lower portion of the nail is thereby completely embedded in the body and consequently is not subjected to excessive wear. It is apparent that when desired, the slots 16 may also be provided in shoes having traction 50 projections on their under surfaces.

55 By my invention there is produced a horseshoe which may be quickly and securely

attached to the hoof and which possesses tractive advantages not possessed by the various shoes now on the market.

I claim:

5. 1. A horseshoe comprising a body, nails secured to said body and extending upwardly and outwardly therefrom and in-turned pointed projections on the upper end of said nails and a plurality of triangular plinths arranged on the lower surface of the body with the apices of the bases of the plinths pointing in different directions.
10. 2. A horseshoe comprising a body having substantially vertical slots in the sides thereof, apertures in said body adjacent said slots, nails secured in said apertures and extending upwardly and outwardly from the bottom of the body and lying partly in said slots and projections on the bottom of said

body adapted to hold the body above the ground, said projections comprising a plurality of triangular plinths with the apices of their bases pointing in different directions.

3. A horseshoe comprising a body, means secured to said body for attaching the shoe and a plurality of triangular plinths, the apices of their bases pointing in different directions disposed upon the lower surface of said body.

In testimony whereof, I have hereunto set my hand at Cupertino, California, this 6th day of February 1915.

JAMES C. KOCONTES.

In presence of—

T. JOLLYMAN,
G. H. BURRUER.
